Specification of Letters Patent.

Patented July 29, 1913.

Application filed January 14, 1913. Serial No. 741,897.

To all whom it may concern:

Be it known that I, HENRY B. FEBIGER, a citizen of the United States, residing in the city of New Orleans, parish of Orleans, 5 State of Louisiana, have invented a new and useful Firearm, of which the following is a specification.

My invention consists of an automatic firearm of the character disclosed in Letters 10 Patent, No. 987,359, granted to me on March 21, 1911, in which the recoil of the breech-block caused by the explosion in the cartridge cocks the hammer and causes the discharge of the shell of the exploded cartridge and the feed of a fresh shell from the magazine.

It further consists of improved means for admitting of the hammer being cocked and remaining so while the trigger is in pulled 20 position.

It further consists of an improved safety-catch which will with absolute certainty prevent the arm from being fired irrespective of how hard the trigger may be pulled.

25 It further consists of improved means for retaining the assembling-screw in place, when the arm is broken down and taken apart.

It further consists of other novel features 30 of construction, all as will be hereinafter fully set forth.

The annexed drawings and the following description set forth in detail one mechanical form embodying the invention, such detail construction being but one of various mechanical forms in which the principle of the invention may be used.

In said annexed drawings: Figure 1 represents an elevation of the right side of the 40 frame and portions of the barrel, fore-end and stock of my improved fire-arm. Fig. 2 represents an elevation of the left side of said parts. Fig. 3 represents an elevation of a portion of the barrel, the fore-end, the 45 barrel-portion of the receiver and the breech-block of the fire-arm. Fig. 4 represents a longitudinal section on the line $x-x$ in Fig. 3. Fig. 5 represents a part elevation and part longitudinal section of as much of the 50 fire-arm as embodies the firing mechanism

of the same, viewed from the left side. Fig. 6 represents a similar part section and part elevation seen from the right side of the arm. Fig. 7 represents a transverse section on the line $y-y$ in Fig. 2.

55 Similar numerals of reference indicate corresponding parts in the figures.

Referring to the drawings, the reference numeral 1 indicates the barrel of my improved fire-arm, having the fore-end or fore-arm, 2, secured to its under-side, and the numeral 3 indicates a part of the stock not shown in the drawings. The receiver, 4, of the gun consists of a barrel-portion, 5, and a stock-portion, 6, similar to the corresponding parts in my above referred to patented arm with the exception that the forward and upper edges of the stock-portion are in the present arm rabbeted to form tongues, 7 and 8, which engage in grooves, 9 and 10, in the 60 forward edge and overhanging top of the barrel-portion. The stock-portion has a trigger-guard, 11, and a magazine guide, 12, like the corresponding portion in the structure disclosed in the above referred to 65 patent, and tangs 13 and 14, secured in the stock in the same manner as in said structure. The stock-portion and barrel-portion of the receiver are secured together by engaging the tongues upon the edges of the 70 stock-portion in the grooves of the barrel portion, and are held clamped together by an assembling-screw, 15, passing through an enlargement, 16, upon the inner side of the wall of the stock-portion and engaging a 75 threaded opening, 17, in the wall of the barrel portion with its threaded end, 18. The assembling-screw has a knurled-head, 19, upon its end, and has a reduced portion, 20, within the enlargement and the bore, 21, 80 90 therein, which reduced portion is engaged by the end of a screw, 22, passing through the enlargement and into the bore, whereby the assembling-screw is retained in the bore when unscrewed from the threaded opening 85 in the barrel-portion.

The hammer, 23, is pivoted upon a screw, 24, within the casing in a similar manner to the hammer disclosed in my Patent, No. 908,553, issued January 5, 1909, and has, 100

like said hammer, a sear-notch, 25, in its fulcrum-end, and an auxiliary sear-notch, 26, in its free-end. Like in the fire-arm of said patent, the hammer has a recess, 27, in 5 its rear edge, into which the end of a main-spring rod, 28, bears, which rod slides in a bearing, 29, upon the lower tang, and is normally forced forward by a main-spring, 30, coiled around the rod and having its 10 ends respectively bearing against a stop, 31, upon the rod and against the bearing 29. A trigger, 32, is fulcrumed in the receiver, below and to the rear of the fulcrum for the hammer, and has a forwardly projecting sear-nose, 33, which may engage the lower sear-notch of the hammer, and a rearwardly projecting arm 34, against the end of which a trigger-spring, 35, bears. A post, 36, is pivoted at its lower end to the 20 rearwardly-projecting arm of the trigger and passes through a longitudinal slot, 37, in the main-spring rod, and the upper end of said post is movably connected by a slot, 68, and pin, 69, to the rear arm of an auxiliary sear, 38, the forward arm of which has a hook or shoulder, 39, adapted to engage the sear-notch in the free end of the hammer. Said auxiliary sear is fulcrumed between two ears, 40, upon the under side of 25 the upper tang. A spring, 41, in the tang bears against and depresses the forward end of the auxiliary sear. A stud, 42, is journaled in the upper tang and has an arm or cau, 43, secured to its inner end, which 30 may be brought in between the end of the post and the tang to prevent the former from being moved upward, when the stud is turned to bring the arm in such position, and the outer end of the stud has a thumb-lever, 44, for turning it, which lever has a lug, 45, upon its under side, which may engage either one of two depressions, 46, in the outer side of the upper tang, so that the stud and its safety-catch arm may be rotated to either have said arm between the 40 end of the post and the tang to prevent the post from being moved when the trigger is pulled, or be swung out of the way of the post to allow the latter to be moved.

50 A breech-block, 47, essentially similar to that disclosed in my Patent No. 987,350, slides in the receiver and upon the inner side of the barrel-portion of the same, and is there guided by a rib, 48, upon the wall of the 55 barrel-portion and by a rib, 49, upon the under side of the overhang of the barrel-portion engaging a rabbet, 50, in the upper corner of the block. A firing-pin, 51, is slideable in the breech-block to have its rear end 60 struck by the hammer when the block is in its forward position. An action-bar, 52, slides in a groove 53, in the wall of the barrel-portion, beneath the breech-block, and has a stud, 54, at its rear end, which

engages an apertured ear, 55, extending 65 downward from the rear end of the breech-block to form a detachable connection between the latter and said bar. The forward portion of said action-bar passes through the forward end of the receiver and into 70 the fore-end, within which is located a tube, 56, secured with its rear end in the receiver and at its forward end to the barrel. The action-bar has at its forward end a guide, 57, sliding upon said tube, and a pin, 58, 75 movable through the tube in slots, 59, in the same, and said pin bears against the forward end of a coiled spring, 60, in the tube, the rear end of which spring bears against the closed rear end of the tube. The tendency of the spring will thus normally be to throw the action-bar and breech block forward. A finger-piece, 61, projects laterally from the action-bar and is movable in a slot, 62, in the wall of the barrel-portion 80 of the receiver. An ejection opening, 63, is formed in said wall, and an ejector, 64, is pivoted in the opposite wall of the receiver, like in the arm of my Patent No. 987,350, to eject the empty shell through 90 such opening. The breech-block has a groove, 65, in its side, with which it slides upon the ejector. An extractor, 66 is provided on the side of the forward end of the breech-block and projects into the side of 95 the chamber of the barrel to extract the shell, as the breech-block recoils. A shield or deflector, 67, is provided above and to the rear of the ejection-opening to deflect the empty shells as they are thrown out. 100

In practice, after a charged magazine has been inserted in the guide and it is desired to fire the arm, the action-bar and breech-block are drawn rearward by means of the finger-piece, cocking the hammer, and again 105 allowed to be drawn forward by the action-spring, when the breech-block will slide a cartridge off from the upper end of the magazine and push such cartridge into the chamber of the barrel. When the trigger is 110 pulled, the hammer strikes the firing-pin, igniting the charge in the cartridge, and the recoil of the exploding cartridge will throw the breech-block rearward to cock the hammer, whereupon the action-spring will again 115 draw the breech-block forward, carrying another fresh cartridge with it into the chamber. As the breech-block recoils, the extractor withdraws the exploded shell, and the ejector throws the same out through the 120 ejector-opening as soon as the recoiling breech-block uncovers the latter. As the action of the recoil of the action-bar and breech-block is almost instantaneous with the pulling of the trigger, and the natural 125 tendency of the gunner is to keep his finger on the trigger after firing, the sear-nose of the trigger cannot engage the lower sear-

notch of the hammer as the latter is thrown back into cocked position, as the hammer would fly forward with the breech block, prematurely firing the cartridge. As however, the slot in the upper end of the post admits of the spring acting against the forward end of the auxiliary sear to depress it, the upper end of the hammer will slip beneath the hook upon such sear and the upper 5 sear-notch will be engaged by said hook and the hammer held in cocked position. When now the trigger is released by the finger, the trigger-spring will throw it forward to bring its sear-nose in contact with the lower 10 end of the hammer so that it will engage the lower sear-notch of the latter when the auxiliary sear disengages the upper notch, which will take place when the trigger-spring depresses the rear arm of the released 15 trigger, drawing the post downward, and the rear arm of the auxiliary sear with it, allowing the hammer to be thrown slightly forward and again be held by the trigger-sear, ready for the next shot.

20 The breech-block is supported from below on the rib 48 and by the ejector engaging the groove in the side of the block, and it is supported against lateral displacement when the gun is broken, by the rib 49, so 25 that the breech-block will not injure the breech-end of the barrel by snapping forward when no cartridge is in the chamber by being out of alinement with the same, which is liable to occur when such complete guidance 30 is not present, and the breech-block will not be liable to drop out from the barrel portion when the gun is taken apart.

By the screw provision retaining the assembling-screw in place, there is no liability 40 of losing the latter when the gun is broken and taken apart. The safety-catch will absolutely prevent the trigger from being pulled when the hammer is cocked, as the thumb-lever must be turned at least one- 45 fourth of a revolution to relieve the cam from engagement with the upper end of the post before the trigger can be pulled. This is of great advantage in a fire-arm which is automatically cocked each time it is fired 50 and in which there is no provision for letting down the hammer after it is cocked. The tongues and grooves in the front and top edges of the barrel and stock portions of the receiver serve to make tight joints between 55 said portions, preventing "spitting", or escape of powder particles and gases while firing.

Other modes of applying the principle of my invention may be employed for the mode 60 herein explained. Change may therefore be made as regards the mechanism thus disclosed, provided the principles of construction set forth, respectively, in the following claims are employed.

Having thus described my invention what 65 I claim as new and desire to secure by Letters Patent, is:—

1. In a fire-arm, a receiver comprising a barrel-portion having an open side and an overhanging top and formed with marginal 70 grooves in its forward side and in the under side of the overhanging top, a stock-portion adapted to fit the open side of said barrel-portion and having tongues upon its forward and upper edges to fit in said grooves, 75 and an assembling screw passed through said portions to secure the same together.

2. In a fire-arm, a receiver portion having an open side and an overhanging top and formed with a longitudinal rib upon the 80 inner face of its side-wall and a longitudinal rib upon the under side of the overhanging top, a receiver portion closing said open side, and a breech-block slidable in said receiver upon said first-recited rib and 85 formed with a rabbet in its upper corner engaged by the rib upon the overhanging top.

3. In a fire-arm, a receiver portion having an open side and an overhanging top and formed with a longitudinal rib upon and a 90 longitudinal groove in the inner face of its side-wall and with a longitudinal rib upon the under side of the overhanging top, a receiver portion closing said open side, a breech-block slidable in said receiver upon 95 said first-recited rib and formed with a rabbet in its upper corner engaged by the rib upon the overhanging top, and an action-bar sliding in the groove in the wall of said receiver portion and movably and detachably 100 connected to said breech-block.

4. In a fire-arm, a receiver portion having an open side and an overhanging top and formed with a longitudinal rib upon the inner face of its side-wall and a longitudinal rib upon the under side of the overhanging top, a receiver portion closing said open side, an ejector pivotally supported in said portion to project in a longitudinal plane from the inner face of the same, and a 110 breech-block slidable in said receiver upon said first-recited rib and formed with a rabbet in its upper corner engaged by the rib upon the overhanging top and formed with a longitudinal groove in its side sliding upon 115 said ejector.

5. In a fire-arm, a hammer formed with a lower sear-notch in its pivoted end and an auxiliary sear-notch in its free end, a trigger having a sear-nose adapted to engage 120 the lower sear-notch and a rearwardly extending arm, a trigger-spring bearing against said arm, an auxiliary sear-lever having a hook upon one arm adapted to engage the auxiliary sear-notch of the hammer, a 125 spring bearing against the hook-arm of said lever, a post pivoted to the rear arm of the trigger and formed with a slot, and a pin in

the sear arm of the auxiliary sear-lever and having play in the slot of said post.

6. In a fire-arm, a receiver formed with a longitudinal slot in one side, a breech-block 5 slidable in said receiver, an action-bar connected to said block and provided with a finger-piece sliding in said slot, and a spring

connected to said action-bar to draw the same forward.
